UNITED STATES PATENT OFFICE.

WILLIE CALEB WILLIAMS, OF MOBILE, ALABAMA.

FLUE CUTTER.

Application filed March 1, 1924. Serial No. 696,261.

To all whom it may concern:

Be it known that I, WILLIE CALEB WILLIAMS, a citizen of the United States, residing at Mobile, in the county of Mobile and

State of Alabama, have invented certain new and useful Improvements in Flue Cutters, of which the following is a specification.

This invention relates to improvements in flue cutters, and particularly to a cutter of this type adapted for use in cutting through tubes, so that they may be removed from boiler sheets.

An object of the invention is to provide a cutter holder and guide which will slip in the end of a boiler tube to position the cutter on the inside of the tube in back of the boiler sheet, a handle being provided for rotating the guide and support in the tube for actuating the cutters, and means being provided which is movable relative to the guide and cutting support for seating the cutters carried thereby outwardly for actively engaging and cutting the tubes.

Another object of the invention resides in providing a cutter support provided with removable and interchangeable guide members which may be removed for the reception of other guide members to adapt the tool for use in connection with various sizes of boiler tubes, ratchet means being also provided for rotating the tube so that it may be readily used in places where the rotation of the handle would be prevented by contact with the boiler walls.

In carrying out the above and other objects, the invention includes a cylindrical body, in which are radially movable, a plurality of cutter members having resilient means for normally drawing said members inwardly in the body, guiding collars being mounted on the body to guide the same into the end of the tube and a handle being rotatably mounted on said body adjacent the outer end thereof, which is formed with an annular flange provided with ratchet teeth, has a pawl connection with said flange and also the ratchet ring arranged in spaced relation therewith, so that the rotation of the handle will operate to rotate the body member and the ring within the boiler tube, while a tapered pin is inserted through said body for seating the cutters outwardly to perform a cutting operation on the boiler tube. This will effectively cut and sever the major portion of the tube from the end portion thereof

which fits into the boiler sheet so that a small ring like end portion, only, remains of the boiler sheet, which may be easily driven out with hammer and chisel.

The invention also includes other objects and improvements in the construction and position of the parts in carrying out the above features, which are particularly pointed out in the following detailed description and claim, directed to a preferred form of the invention, it being understood, however, that variations may be made in the specific construction of the parts and the arrangement thereof, without departing from the spirit and scope of the description and claim.

In the drawing, forming a part of the application:

Figure 1 is a sectional view through a portion of the cover sheet, showing one of the flue tubes and the tube cutter constructed according to this invention, in operative position for cutting the tube, the parts being shown in elevation;

Fig. 2 is a view similar to Fig. 1, the parts of the invention being shown in longitudinal section;

Fig. 3 is an end view of the flue cutter;

Fig. 4 is a sectional view, taken on the line 4—4 of Fig. 1;

Fig. 5 is a detail perspective view of one of the cutter elements and its mounting; and

Fig. 6 is a detail perspective view of one of the springs carried by the handle for operating one of the pawls engaging the ratchet.

1 indicates a boiler sheet of the usual and well known form, and 2 a flue or boiler tube mounted in said sheet in the usual and well known manner, forming an assembled boiler structure.

The flue cutter includes the cylindrical body member 3, having an annular projecting flange at the outer end thereof indicated at 4, and provided with peripheral ratchet teeth 5. A ratchet collar 6 is fixedly mounted on the member 3 in spaced relation to the annular flange 4 and is provided with peripheral ratchet teeth 7 disposed in a direction opposite to the teeth 5 on the flange 4, the said ratchet collar being spaced from the flange 4 a distance sufficient to permit the mounting and free rotation of the handle assembly 8, between the flange and the collar.

The handle assembly includes an operating lever 9, having a semi-circular recess in one end thereof adapted to fit the periphery

of the cylindrical body 3; and adapted to receive a cooperating U-grip 10, which is secured to the ends of the handle portion 8, by bolts 11 and secure said lever in rotatable relation on the body 3. The operating lever 9 is provided with a pair of projections 12 which are formed with aligned openings for receiving a rod 13 carrying a handle 14 at the outer end thereof, said rod being slidably in said projection and adapted to be secured in rigid relation in connection with the operating lever 9 by the set screw 15 threadably mounted in said projection and adapted to be operated to lock said rod in connection therewith. Pawls indicated at 16 are pivotally mounted on opposite sides of the operating lever 9 and in opposite relation with one another for engagement with the ratchet teeth on the peripheries of the flange 4 and the ratchet collar 6, so that in the rotation of the operating lever by the handle 14, one or the other of the pawls will cooperate with the respective ratchet teeth so that the body 3 may be rotated in either direction. A projection 17 is mounted adjacent the central portion opposite each pawl for receiving a coil spring 18 which is projected against the pawl and adapted to move the same into engagement with its respective ratchet. Releasing members 19, clearly shown in detail in Figure 6, are mounted in the operating lever 9, and are operable for throwing the pawls 16 out of engagement with their respective ratchet, so that in the operation of the handle assembly, one or the other of the pawls can be set, and the other released, so as to rotate the body 3 in one direction only.

The central portion of the body 3 is formed with a plurality of openings 20, through which project the cutter carrying members 21 which are formed of substantially arcuate base sections 22, having a pair of outwardly directed ears 23, which are adapted to extend through the opening 20 in the body 3, and to support a cutter element 24 for rotation on a pin 25, beyond the periphery of the body 3, so that the same may engage the inner side of the boiler tube 2, for accurately cutting the same. The retracting springs 26 are mounted within the body 3 and are seated in the arcuate base section 22 of the cutter carrying member for normally drawing said members inwardly toward the axis of the body 3. A pair of guide collars 27 of a suitable outer diameter for sliding engagement in the tube 2 are removably mounted on the body 3, and are interchangeable with each other or may be removed for receiving guide collars of a larger diameter for cooperation with a larger tube. These collars position the body 3 in axial relation with the tube, so that the cutter members are directed radially outwardly against the inside surface of the tube

when operated to cut the same. An annular ring member 28 having an outer diameter substantially larger than the guide collars 27 is positioned between the inner guide collar and the ratchet ring 6, for engagement with the end of the boiler tube outside of the boiler sheet, as shown in Figures 1 and 2, in order to limit the insertion of the body 3 into the boiler tube. This also limits the movement of the cutters into the boiler tube so that the tube is severed at a point just inside of the inner wall of the boiler sheet. This annular ring, also serves in co-operation with the guide ring 27 to position the body 3 in a proper relation with the boiler tube. A tapered pin 29 is provided for insertion through the body 3 and for engagement with the inner arcuate faces of the cutter carrying members 21, so that said members may be forced outwardly against the inner face of the boiler tube or flue for cutting cooperation therewith, the pin being driven inwardly as the cutters sever the tube so as to cut it entirely through and sever it from the end portion of the flue in the boiler seat, following which the pin is withdrawn, followed by the withdrawal of the body 3, which will permit the main portion of the tube within the boiler to drop away from the end of the boiler sheet and also leave a small ring of tube material in the sheet which can be readily driven out with hammer and chisel.

From the above description, it will be seen that a very simple and convenient form of tool has been provided, for cutting boiler flues or tubes to sever the main portion of the tube in the boiler from the part in the end wall, in order to remove old and burnt out tubes from the boiler sheet for replacement with new ones, the removal of the small ring of material left in the sheet being very easily accomplished by hammer and chisel, as the short end is very weak after the severance of the main portion of the tube therefrom.

The tool is adapted for operation in most any position, especially in the corners of the boiler adjacent the fire box wall by reason of the ratchet structure of the operating lever 9, so that the turning of the body 3 may be effected by relatively small movement of the handle assembly 8.

What is claimed is:

A boiler tube cutter including a cylindrical tubular body having an integral annular flange at its outer end provided with peripheral ratchet teeth, a ratchet collar fixedly mounted on the body in spaced relation to said flange, an operating handle rotatably mounted between said flange and said collar, independently operable pawls pivotally mounted on the operating handle and adapted for independent cooperation with the ratchet teeth on said flange and collar for

effecting a rotation of the body in the direction of movement of the handle, said body being provided between its ends with circumferentially spaced openings, a pair of longitudinally spaced guide rings removably mounted on the body on opposite sides of said openings, cutting elements extending through said openings and having their inner ends disposed within the tubular body, the inner ends of said cutting elements being of ar-

cuate formation, spring means anchored on said body and connected with said cutting element to normally move the latter inwardly, and an expanding pin inserted into said body and having an inner tapered end upon which the arcuate inner portions of said cutting elements are engaged. 15

In testimony whereof I affix my signature.

WILLIE C. WILLIAMS.
